TELEVISION APPARATUS

Alda V. Bedford, Collingswood, N. J., assignor to
 Radio Corporation of America, a corporation of
 Delaware

Application October 31, 1935, Serial No. 47,564

9 Claims. (Cl. 178—7.2)

My invention relates to cathode ray tube deflecting circuits and particularly to circuits designed to supply saw-tooth waves to the cathode ray tube deflecting plates or deflecting coils.

5 This application is a continuation in part of application Serial No. 755,304, filed November 30, 1934, and assigned to the Radio Corporation of America.

10 When deflecting plates are employed for deflecting a cathode ray, it is the usual practice to supply a saw-tooth wave to the deflecting plates through a power tube and a transformer. It has been found that in such a circuit there is distortion of a saw-tooth wave such that if a 15 saw-tooth wave of perfect wave form is supplied to the power tube it appears across the deflecting plates as a saw-tooth wave which is "bent over," that is, the main portion of the saw-tooth is curved instead of straight.

20 The same difficulty is encountered when deflecting coils are employed, this being true whether the deflecting coils are coupled to the output tube through a transformer or through impedance coupling comprising a choke coil and 25 coupling condenser.

One object of my invention is to provide an improved cathode ray tube deflecting circuit which substantially overcomes the above-mentioned difficulty.

30 More specifically, an object of my invention is to provide an improved deflecting circuit which supplies waves of substantially perfect saw-tooth wave form to the deflecting plates or coils of a cathode ray tube.

35 A still further object of my invention is to provide a circuit which supplies to cathode ray tube deflecting plates or coils waves which have a substantially perfect saw-tooth wave form and which are suitably modified to provide correction for the so-called "keystone" effect obtained in cathode ray tubes having an inclined screen.

In a preferred embodiment of my invention I employ a capacitor-resistor network for pre-distorting a saw-tooth wave before it is impressed upon the input circuit of the power tube. This network is so adjusted that it acts preferentially upon the low frequency components of the saw-tooth wave, this preferential action accentuating the amplitude of the low frequency components and also producing a shift in their phase.

40 In one particular embodiment of my invention, a capacitor-resistor network is employed which filters out from the horizontal deflecting waves all low frequency components which have been added as a result of the keystone correction. This same network also pre-distorts the horizontal deflecting waves to compensate for distortion unavoidably produced in the output circuit of the power tube.

Other objects, features and advantages of my invention will appear from the following description taken in connection with the accompanying drawings, in which

Figure 1 is a circuit diagram of a television 5 transmitter embodying my invention.

Fig. 2 is a simplified plan view of the cathode-ray transmitter tube shown in Fig. 1.

Fig. 3 is a similar side view of the above-mentioned cathode-ray tube. 10

Fig. 4 is a circuit diagram showing a modification of a portion of the circuit shown in Fig. 1.

Figs. 5 to 10 are curves which are referred to in explaining the keystone correction feature 15 of my invention.

Figs. 11 and 12 are curves which are referred to in explaining the vertical deflection correcting feature of my invention.

Fig. 13 is a circuit diagram showing a modification of another portion of the circuit shown in Fig. 1, and 20

Figs. 14 and 15 are curves which are referred to in explaining the operation of the saw-tooth pre-distorting network. 25

Referring to Fig. 1, the television transmitter includes a cathode-ray transmitter tube 1 of the type which is described in an article by V. K. Zworykin, published in the January, 1934, issue of the Proceedings of the Institute of Radio Engineers. This tube includes an electron gun consisting of a cathode 3, a control electrode 5 and a first anode 7. A second anode 9 is provided which, in addition to accelerating the electrons, aids in the electrostatic focusing of the 35 electron beam. The second anode also functions as a collector of photo-electrons which are emitted from a mosaic 11 of light-sensitive elements.

The light-sensitive elements of the mosaic 40 11 are insulated from each other and from a metallic back plate, as described in the above-mentioned publication.

An optical image of the object 13 to be transmitted is projected upon the mosaic 11 by means 45 of a suitable optical system 15. In order that the light-sensitive surface of the mosaic 11 may have the optical image projected thereon and, at the same time, be scanned by the electron beam, it is positioned at an acute angle to the 50 longitudinal axis of the cathode-ray tube. More specifically, it is positioned at an acute angle to the axis of the electron gun.

The cathode-ray tube 1 is provided with suitable deflecting devices, such as deflecting plates 55 17 and deflecting coils 19, for deflecting the electron beam both horizontally and vertically to scan the mosaic 11. If an optical image is projected upon the mosaic, picture signals are developed during the scanning of the mosaic by 60

the electron beam, these picture signals appearing across a resistor 21 which is connected between the mosaic back plate and ground. These picture signals are supplied to a suitable transmitter 23 or to a transmission line for transmission to a receiver.

Because of the angular position of the mosaic 11 with respect to the electron gun, certain corrections must be made in both the horizontal and vertical deflection of the electron beam. That such corrections are necessary will be apparent by referring to Figs. 2 and 3, like parts in these figures and Fig. 1 being indicated by the same reference numerals. In Fig. 2 the dotted lines 15 25 indicate the limits of the horizontal deflection of the electron beam. It will be evident that when the beam is striking the lower portion of the mosaic 11 it traverses a shorter path thereon than it does when it is striking the upper 20 edge of the mosaic, providing the angle between the limits of the horizontal deflection remains constant as the beam is deflected upwardly. As a result, the beam scans a keystone shaped area on the mosaic that is indicated by the area enclosed in dotted lines 21. One of the main objects of my invention is to so correct the horizontal deflection that a rectangular, rather than a 25 keystone, shaped area is scanned on the mosaic.

In Fig. 3 the dotted lines indicate several positions 30 of the electron beam as it is deflecting upwardly on the mosaic. From inspection of this diagram it will be apparent that, for a given angular upward deflection of the electron beam, it traverses a longer path on the mosaic at the 35 top thereof than it does at the bottom. As a result, unless a suitable correction is made, the picture appearing at the receiver will be crowded together in the lower region of the picture.

Referring now to the deflecting circuits shown 40 in Fig. 1, the vertical deflecting circuit for supplying a saw-tooth current to the deflecting coils 19 is indicated generally at 29, while the horizontal deflecting circuit for supplying a saw-tooth voltage to the deflecting plates 17 is indicated generally at 31.

Both deflecting circuits are controlled by an impulse generator 33 which generates horizontal deflecting impulses at a comparatively high frequency and vertical deflecting impulses at a comparatively low frequency. In the particular embodiment illustrated the horizontal deflecting impulses occur at the rate of 10,290 per second, while the vertical deflecting impulses occur at the rate of 60 per second. The impulse generator 33 may be of any suitable type, one form comprising a disc driven by a synchronous motor, the disc containing openings therein through which light is projected upon a photo-electric cell. An impulse generator of this type is shown in French Patent No. 742,671, dated January 4, 1933, and, as applied to interlaced scanning, in Ballard application Serial No. 623,325, filed July 19, 1932, and assigned to the Radio Corporation of America. While the frequencies of the deflecting impulses given above are for a system employing interlaced scanning, it will be understood that my invention is not limited to such a system.

The vertical deflecting circuit includes an amplifier tube 35, a discharge tube 37, and an output tube 39. The particular amplifier tube 35 illustrated is of the pentode type having a cathode 41, a control grid 43, a screen grid 45, a suppressor grid 47 and a plate 49. The control grid 43 is provided with a suitable bias potential 70 by means of the usual self-bias resistor 51 which

is shunted by a by-pass condenser 53. The screen grid 45 and plate 49 are supplied with positive potentials from a suitable unidirectional plate or "B" voltage supply (not shown) through filter resistors 55 and 57, respectively. Suitable 5 by-pass or filter condensers 59 and 61 are provided in the screen grid and plate circuits.

The vertical deflecting impulses are impressed upon the input circuit of the amplifier tube 35 through a resistor 63 and a coupling condenser 10 65.

The output circuit of the amplifier tube is coupled by means of resistance coupling to the input circuit of the discharge tube 37. The discharge tube 37 may be of the three-element type, as 15 illustrated, comprising a cathode 67, a control grid 69 and a plate 71. The grid leak resistor 70 has a resistance value which is high enough to bias the tube 37 substantially to cut-off during the intervals between impulses, said impulses causing the grid to collect electrons. 20

As is well known, in order to produce a flow of current through the deflecting coils 19 which has a good saw-tooth wave form, it is necessary that the voltage impressed across the coils 25 contain a saw-tooth component in addition to the impulse component which would be required if the deflecting coil circuit were purely inductive. This saw-tooth component is provided by charging a condenser 73 from the plate 30 voltage supply through a highly resistive circuit which includes a filter resistor 75, a variable resistor 77 and a fixed resistor 79. This charging circuit also includes another variable resistor 81, which has a comparatively low resistance value, for supplying the necessary voltage impulse component. The positive potential for the plate 71 of the discharge tube 37 is supplied through the filter resistor 75 and the resistors 77 and 79. 40

In operation, the vertical deflecting impulses which are supplied from the impulse generator 33 are given a negative polarity whereby they appear in the input circuit of the discharge tube 37 as impulses of positive polarity. The grid 69 45 of the discharge tube 37 normally is sufficiently negative to substantially block plate current flow between the deflecting impulses. The condenser 73, which will be referred to as the vertical saw-tooth condenser, is charged at a substantially 50 constant rate through the high impedance circuit 75—77—79, whereby the voltage across the condenser 73 gradually increases in value. As soon as a positive impulse appears on the control grid 69, the discharge tube 37 becomes highly conductive, whereby the condenser 73 discharges very rapidly through the resistor 81 and the discharge tube. This discharge through the resistor 81 gives the desired impulse component to the voltage wave supplied to the input circuit of the tube 39. The charge and discharge of the condenser 73 produces a saw-tooth voltage wave thereacross. 55

The combined saw-tooth component and impulse component are impressed through a coupling condenser 83 and a resistor 85 upon the input electrodes of the tube 39. 60

The output tube 39 may be of the pentode type comprising a cathode 87, a control grid 89, a screen grid 91, a suppressor grid 93 and a plate 70 95. The tube is provided with the usual self-bias resistor 97 and by-pass condenser 99. The screen grid 91 is supplied with positive potential through a filter resistor 101, while the plate 95 is supplied with positive potential through a choke 75

coil 103 and a resistor 105. The choke coil 103 is provided mainly for the purpose of maintaining the amplification at a proper level for high frequency components of the wave.

5 The input circuit of the output tube 39 includes a resistor 107 and a condenser 109 connected in series, the condenser 109 being shunted by a variable resistor 111. The purpose of the condenser 109 and variable resistor 107 is to control the 10 wave shape of the current flowing through the vertical deflecting coils 19, whereby the above-mentioned correction may be made for the vertical deflection. This feature of the invention will be explained in detail hereinafter. The output 15 circuit of the output tube 39 is coupled to the deflecting coils 19 through a suitable coupling condenser 113.

Referring now to the horizontal deflecting circuit 34, it includes an amplifier tube 115, a discharge tube 117, a second amplifier tube 119 and an output tube 121. The amplifier tube 115 may be of the pentode type comprising the usual cathode, control grid, screen grid, suppressor grid and plate. It is provided with a suitable negative bias 20 by means of a self-biasing resistor 123. The plate is supplied with a positive potential through a conductor 125 and through a plate resistor 127. The screen grid is supplied with positive potential 25 through the conductor 125 and through a filter resistor 129, a "bleeder" resistor 128 being connected between the screen grid and ground.

The horizontal deflecting impulses are impressed upon the input circuit of the amplifier 115 through a resistor 131 and a coupling condenser 133. The amplified impulses are impressed through a coupling condenser 135 upon the input circuit of the discharge tube 117.

The discharge tube 117 is of the screen grid type, the tube illustrated being a pentode comprising a cathode 137, a control grid 139, a screen grid 141, a suppressor grid 143 and a plate 145. The tube 117 is biased at a suitable negative potential by means of a self-biasing resistor 147. The plate 145 is supplied with positive potential 40 through the conductor 125, a filter resistor 149, a buffer resistor 151, and a plate resistor 153. It will be noted that the resistors 147 and 149 are provided with by-pass condensers.

The screen grid 141 is supplied with positive 50 potential through the conductor 125 and through a resistor 155. The resistor 155, together with a resistor 157 connected between the screen grid 141 and ground, forms a potentiometer connected across the plate voltage supply for lowering the 55 screen grid voltage to the desired value. The resistors 157 and 155 also function as a grid leak resistor for the screen grid.

In addition to the steady voltages supplied to the plate and screen grid through the above-described circuits, saw-tooth voltages are impressed upon the plate 145 and the screen grid 141 through a circuit which will be described later.

In order to produce the saw-tooth voltage 65 which is to be applied to the deflecting plates 17, a condenser 159 is provided which is charged through the three resistors 149, 151 and 153. The condenser 159 is discharged periodically through the discharge tube 117 to produce a saw-tooth 70 voltage wave across the condenser 159 in the same manner as described in connection with the vertical deflecting circuit.

The saw-tooth voltage is impressed through a coupling condenser 161 upon the input circuit of 75 the amplifier tube 119. This tube may be of the

pentode type, comprising the usual cathode, control grid, screen grid, suppressor grid, and plate. A positive potential is supplied to the screen grid through the conductor 125 and a filter resistor 163. A positive potential is supplied to the plate 6 through the conductor 125, the filter resistor 163, a variable wave-shaping resistor 165, and a plate resistor 167.

In order to permit a control of the deflecting voltage wave shape, a condenser 169 is connected 10 in series with the plate resistor 167 and ground whereby the amplitude of low frequencies is exaggerated. The extent to which the lower frequencies are amplified more than the higher frequencies is determined by the extent to which signals 15 are shunted around the condenser 169 by the variable resistor 165.

The amplified saw-tooth wave which appears across the resistor-condenser combination 167—169 is impressed upon the input circuit of the output tube 121. In the embodiment illustrated, the output tube 121 is of the three-electrode type comprising of a cathode 171, a control grid 173, and a plate 175. The input circuit of the tube 121 includes a resistor 177 and a resistor 179 to 20 which the control grid 173 is connected through a variable tap for the purpose of controlling the amplitude of the deflecting voltage wave. The resistors 177 and 179 are shunted by a small capacity condenser 181 for the purpose of filtering 25 out the highest frequencies in the saw-tooth wave which might produce undesired resonant effects in the transformers 183 and 185 which couple the deflecting plates 17 to the output circuit of the tube 121. It will be noted that the tube 121 30 is provided with the desired negative bias by means of a self-biasing resistor 187, while the plate potential is supplied through a filter resistor 189 and the primary of the output transformer 183. The output transformer couples the 35 output circuit of the tube 121 to a cable, indicated by the dotted lines 191, which extends from the horizontal deflecting circuit to the cathode-ray tube 1. This transformer steps down the voltage 40 to a value low enough to make the shunting effect 45 of the distributed capacity of the cable negligible.

The auto-transformer 185, which is located in the immediate vicinity of the cathode-ray tube 1, is provided for stepping up the deflecting voltage to the high value required for deflecting 50 the electron beam.

It will be noted that in the above-described circuits all filter resistors and self-bias resistors are provided with suitable by-pass condensers.

If the correcting network 167—169—165 were 55 not provided in the above-described circuit, the saw-tooth voltage appearing across the deflecting plates 17 would be distorted or "bent over" as indicated by the curve B in Fig. 14. In the particular horizontal deflecting circuit shown in 60 Fig. 1, this distortion of the saw-tooth wave form is caused largely by the transformers 183 and 185.

The reason for the distortion was not fully understood for some time. Measurements showed that there was a certain loss in low frequency 65 components, which loss would cause a saw-tooth wave to "bend over". However, this loss was not great enough to account for a distortion of the magnitude encountered. It was finally discovered that the explanation was in the phase shift 70 of the saw-tooth components at low frequencies.

The effect of phase shift can readily be seen by referring to Fig. 14 where curves C and D show the phase relation of two sine-wave components of the perfect saw-tooth wave indicated 75

at A. Now assume that the phase of the component C is shifted with respect to the higher frequency components, as indicated at E. Obviously, the general effect is to produce a distorted saw-tooth wave as indicated at B.

Therefore, the reason that my capacitor-resistor network 167—169—165 is effective to provide a perfect saw-tooth voltage wave across deflecting plates 17 is that it not only accentuates the low frequency components but it also shifts their phase (advances their phase) to compensate for a retardation in their phase produced in the utilization network.

My capacitor-resistor network is equally effective when employed in a deflecting circuit having deflecting coils as will be more clearly understood from a description of the action of the network 107—109—111 which is given later. While this network will be described as being provided for the purpose of controlling the degree of "bending over" of a saw-tooth wave, it will be understood that in circuits where a "bent" saw-tooth is not desired the same network may be employed to prevent "bending over".

It may be noted that the wave shape of the pre-distorted saw-tooth voltage appearing across the input of output tube 121 is substantially as shown in Fig. 15. It will be seen that, as a result of both phase shift and accentuation in amplitude of low frequency components, the saw-tooth "bends up" to compensate for the "bending over" produced in the deflecting or utilization network.

Referring to the keystone correcting portion of the circuit, it includes an amplifier tube 193 which may be of the pentode type as illustrated. The input circuit of the tube 193 is connected across the saw-tooth wave condenser 73 in the vertical deflecting circuit by means of a coupling condenser 195 and a connection through ground.

A positive potential is supplied to the plate of the pentode 193 from the plate supply through the conductor 125 and resistors 197 and 199 which are connected in parallel. A resistor 201 is included in the circuit to lower the plate voltage to the desired value. Resistors 197 and 199 are provided with a by-pass condenser 203.

It will be apparent that a substantially pure saw-tooth wave appears across the resistors 197 and 199 and that this wave is 180° out of phase with respect to the saw-tooth wave appearing across the condenser 73, the phase having been reversed by the amplifier tube 191. The saw-tooth wave appearing across the resistors 197 and 199 is shown in Figures 8 and 10.

In accordance with my invention, this saw-tooth wave is utilized for modulating the voltages applied to the plate 145 and screen grid 141 of the horizontal circuit discharge tube 117 whereby the amplitude of the horizontal deflection is gradually decreased as the electron beam is deflected upwardly, the electron beam always being deflected substantially the same amount to the right as to the left of the center of the mosaic.

In order to modulate the plate voltage, the point intermediate the two resistors 151 and 153 is connected through a coupling condenser 205 and a variable tap to a point on the resistor 197. The plate modulation is produced by the flow of vertical saw-tooth current through the plate resistor 153 whereby a voltage corresponding to this current is added to the steady voltage provided by the plate supply.

The screen grid 141 of the discharge tube 117 is connected through a coupling condenser 207 to

the plate end of the resistors 197 and 199 whereby a vertical saw-tooth voltage modulates the screen grid voltage due to the flow of vertical saw-tooth current through the screen grid resistor 157.

The relative values of the plate modulating voltage and the screen grid modulating voltage may be adjusted by means of the variable tap on the resistor 197. The values of both modulating voltages may be adjusted simultaneously after the desired balance has been obtained by adjusting the value of the resistor 199 which is made variable for this purpose. It will be seen that, as the electron beam is deflected upwardly, the keystone correcting circuit causes a gradual reduction in the voltages on the plate and screen grid of the discharge tube 117 since the vertical saw-tooth wave is decreasing in value as indicated in Fig. 8. The operation of the circuit will be better understood by referring to Figures 5 to 10.

In Fig. 5 there is shown a series of charging curves for the saw-tooth condenser 159 in the horizontal deflecting circuit. The upper curve 209 shows how the voltage increases across the condenser 159 as it is charged through the resistors 149, 151 and 153 with a certain voltage applied to the condenser-resistor combination. The lower curves 211, 213, 215 and 217 show how the voltage across the condenser 159 builds up for lower voltages applied to the same condenser-resistor circuit.

The curves in Fig. 6 show how the voltage across the condenser 159 varies as the said condenser discharges through the discharge tube 117 with different voltages applied to the discharge tube screen grid 141. The steepest discharge curve 219 represents the case where a comparatively high positive voltage is applied to the screen grid 141. The other curves 221, 223, 225 and 227 show how the condenser 159 discharges less rapidly as the positive voltage on the screen grid 141 is decreased.

Referring to Fig. 7, there are illustrated two saw-tooth curves. The upper curve 229 is the one which would be generated with the keystone correcting circuit omitted, that is, with no modulation on the plate and screen grid of the discharge tube 117. This curve has been constructed by means of the top curve 209 in Fig. 5 and the top curve 219 in Fig. 6. It will be seen that the condenser 159 charges gradually along the curve 209 during the time T_1 and discharges suddenly along the curve 219 during the time T_2 . It will be understood that during the time T_1 the discharge tube 117 is biased beyond cut-off, while during the time T_2 to a positive synchronizing impulse is being impressed upon the control grid of the discharge tube 117 to render it highly conductive. Only a small number of horizontal saw-teeth for each vertical saw-tooth has been indicated in Figs. 7 and 8 in order to simplify the drawing.

If an attempt is made to gradually reduce the amplitude of the horizontal saw-tooth wave by modulating only the plate voltage of the discharge tube 117, the resulting saw-tooth has the appearance of the lower saw-tooth wave 231. This saw-tooth wave has been constructed from the several curves in Fig. 5, since it is assumed that the charging voltage is being reduced gradually by the saw-tooth voltage indicated in Fig. 8, and from the top discharge curve 219 in Fig. 6. It has been assumed that the discharge rate of the condenser 159 has not changed, even though the plate voltage of the discharge tube 117 has

been lowered, because, for all practical purposes, this is true for tubes of the screen grid type. Since the discharge rate has remained the same, the average value of the voltage across the condenser 159 has decreased in value as indicated by the saw-tooth curve. Obviously a saw-tooth wave of this character would produce a distorted picture. Specifically, it would produce a picture which would not have vertical sides.

If a three element vacuum tube were employed in place of the screen grid tube 117, the effect illustrated by the saw-tooth curve 231 would not be so pronounced since the discharge rate of the condenser 159 would change appreciably with a change in plate voltage. For this reason, by utilizing a triode discharge tube with modulation on its plate only, a keystone correction may be obtained which is appreciably better than no correction, but the correction will be imperfect.

Fig. 9 illustrates the keystone correction that is obtained by means of the circuit illustrated in Fig. 1. The saw-tooth curve 233 illustrated in this figure has been constructed by means of the charging curves shown in Fig. 5 and the discharge curves shown in Fig. 6, since the charging voltage and the screen grid voltage are being reduced gradually by the saw-tooth voltage indicated in Fig. 10. It is evident that by decreasing the discharge rate of the condenser 159 at the same time that its charging rate is decreased, it is possible to maintain the average voltage across said condenser substantially constant. Considering the curves 231 and 233 in Figs. 7 and 9, respectively, from a slightly different view point, the saw-tooth curve 231 is objectionable because it contains a strong vertical saw-tooth component whereas the saw-tooth curve 233 contains no such component. It has been found from experience that my improved keystone correcting circuit is reliable in operation and that it gives a practically perfect correction of the keystone effect.

Referring now to the previously mentioned correcting circuit for the vertical deflection error illustrated in Fig. 3, I correct for this error by causing the vertical deflecting saw-tooth wave to bend over as will be understood by referring to Fig. 11.

Referring to Fig. 11, if it were not for the fact that the mosaic 11 is at an angle with respect to the electron gun, for the vertical deflection, a perfect saw-tooth current wave would be desired as indicated at 235. As previously pointed out, however, it is desired to slow down the deflection of the electron beam as it is deflected upwardly. The saw-tooth may be "bent over" with a resulting slowing down of the electron beam by eliminating some of the low frequency components of the saw-tooth wave 235, the saw-tooth wave 235 being the one which appears across the saw-tooth condenser 73. In the vertical deflecting circuit illustrated in Fig. 1, the coupling condenser 113 and the by-pass condenser 99 are deliberately made small enough in capacity to eliminate enough low frequencies for bending the saw-tooth curve over more than it is desired for the correction. The resulting saw-tooth curve is indicated at 237. The saw-tooth curve indicated at 239 is the one which is desired for obtaining a perfect vertical deflection correction. The saw-tooth wave is raised from the position of curve 237 to the position of curve 239 by means of the correcting circuit 107-109-111, previously described, which accentuates the lower frequencies. By varying the resistor 111, the vertical de-

flecting saw-tooth curve may be made to occupy almost any position between the two saw-tooth curves 237 and 235.

The curves in Fig. 11 represent both the flow of current through the vertical deflecting coils and the saw-tooth component of the voltage impressed upon the input electrodes of the amplifier. The wave shape of the voltage impressed upon the input electrodes of the amplifier 39 is indicated by the curve in Fig. 12. It will be seen that this voltage includes the necessary impulse component for producing the flow of saw-tooth current through deflecting coils.

In Fig. 4 there is illustrated another circuit for controlling the curvature of the vertical saw-tooth wave. Like parts in Figs. 1 and 4 are indicated by the same reference numerals. In the circuit of Fig. 4, the condenser 109 and resistors 107 and 111 of Fig. 1 have been replaced by a variable grid leak resistor 241. Also, the condensers 113 and 99 in the circuit have been given a capacity sufficient to pass the low frequency components of the saw-tooth wave efficiently. The curvature of the saw-tooth wave is controlled by adjusting the grid leak resistor 241 until the low frequency components are attenuated to the desired degree.

In some cases it may be preferred to deflect the electron beam from the edge of the mosaic farther from the electron gun to the edge of the mosaic nearer the gun, that is, from top to bottom in the cathode-ray tube illustrated. It will be apparent that, in such a case, the speed of vertical deflection should be increased as the beam approaches the bottom edge of the mosaic. This may be accomplished by so adjusting the grid leak resistor 111 of Fig. 1 that the saw-tooth wave bends upward above the line of a perfect saw-tooth, instead of downward.

Also, if the beam is deflected downwardly, the amplitude of the horizontal deflecting saw-tooth must be increased as the beam approaches the bottom edge of the mosaic, this being accomplished merely by applying a vertical deflecting saw-tooth wave to the discharge tube 117 which is 180 degrees out of phase to that assumed in describing Fig. 1. In other words, both the charging voltage and the positive screen grid voltage are increased as the beam is deflected downwardly. The change in amplitude of the charging voltage and in the amplitude of the positive screen grid voltage is always in the same sense, that is, the charging voltage and the screen grid voltage either increase together or decrease together.

In Fig. 13 there is illustrated a modification of a portion of the horizontal deflecting circuit shown in Fig. 1. The circuit shown in Fig. 13 may replace that portion of the circuit in Fig. 1 which is at the right of the coupling condenser 161. It will be noted that the amplifier tubes 119 and 121 in this case are replaced by three tubes 300, 301, and 302. It will also be noted that deflecting coils 303 are employed instead of deflecting plates although, of course, deflecting plates may be employed, if preferred.

The amplifier tube 300 may be of the screen grid type, the plate 304 of which is supplied with voltage through a filter resistor 306 and a plate resistor 307. The filter resistor 306 is shunted by the usual by-pass condenser 308.

In accordance with my invention, the output circuit of the amplifier tube 300 is coupled to the input circuit of the next amplifier tube 301 through a capacitor-resistor network, indicated

generally at 309, this network serving the double purpose of filtering out any vertical deflecting frequency components which may be present in the horizontal deflecting circuit and pre-distorting the horizontal saw-tooth deflecting waves in order to compensate for distortion produced in the deflecting coil circuit.

The amplifier tube 301 may be of the screen grid type, the plate 311 of which is supplied with an operating voltage through a filter resistor 312 and a plate resistor 313. The filter resistor 312 is shunted by the usual by-pass condenser 314.

The saw-tooth voltage appearing in the output circuit of the amplifier tube 301 is impressed upon the input circuit of a power amplifier which, in the particular circuit being described, consisted of two power tubes 302 of the 247 type connected in parallel. Because of the high plate impedance of a tube of this type, a saw-tooth voltage component is all that is necessary in order to produce a perfect saw-tooth current through the deflecting coils 303. In other words, the impulse component, which is required when the output tube has a low plate impedance, may be neglected in this circuit.

In order to obtain efficient transfer of energy from the power tube 302 to the deflecting coils 303, which have a low impedance, the output circuit of the power tube is coupled to the coils 30 through a transformer 316.

The network 309 consists of two filtering and correcting stages. The first stage consists of a filter section, comprising condenser 317 of small capacity, and a resistor 318, and a correcting section comprising a second resistor 319 and a second condenser 321, all connected in series between the plate 304 and ground. The condenser 321 is shunted by a variable resistor 322. In operation, condenser 317, because of its small capacity, eliminates a large percentage of the comparatively low frequency components of the vertical deflecting saw-tooth impulses. This filtering action unavoidably removes a small percentage of the low frequency components from the horizontal deflecting saw-tooth waves, although these components have a considerably higher frequency than the components of the vertical deflecting saw-tooth waves. In order to compensate for this undesired loss, and also in order to exaggerate the amplitude and shift the phase of the low frequency components of the horizontal deflecting waves, the resistor 319 and condenser 321 are utilized. By adjusting the resistor 322, the low frequency components of the horizontal deflecting waves may be accentuated in the desired manner to give the necessary pre-distortion, as described in connection with the network 167-169-165 shown in Fig. 1.

Because the filtering and the pre-distorting action of the first network stage is not perfect, the second stage is employed, this stage consisting of the small capacity condenser 323, a resistor 324, a second resistor 326 and a second condenser 327. As in the first network stage, the second condenser 327 is shunted by a variable resistor 328. The action of the second network stage is identical with that of the first stage, the condenser 323 and resistor 324 operating to remove vertical deflecting components and the resistor 326 and condenser 327 operating to increase the amplitude and shift the phase of the low frequency components of the horizontal deflecting waves.

It has been found that the operation of the transmitter is fairly satisfactory when no attempt

is made to filter out vertical deflecting components. Therefore, the specific circuit shown in Fig. 1 is the preferred one at the present time. However, a small amount of vertical deflecting components usually appears in the output of the horizontal deflecting circuit because of difficulty in "balancing" the circuit and, as the art progresses, it may be desired to remove this component by means of the filter network illustrated in Fig. 13. Attention is called to the fact that in Fig. 13 the portion of the network 309 which acts upon the low frequency components of the horizontal deflecting waves is the same as the network 167-169-165, provided for the same purpose in Fig. 1.

From the foregoing description it will be seen that I have provided correcting circuits which enable an operator to so control the horizontal and vertical deflections of the transmitter tube electron beam that an undistorted picture is transmitted even though the transmitter tube mosaic is positioned at an angle with respect to the electron gun. It will also be seen that I have provided means either for impressing a substantially perfect saw-tooth wave across a pair of deflecting plates or for forcing a substantially perfect saw-tooth current through deflecting coils.

In the embodiment of my invention illustrated in Fig. 1, certain of the circuit values were as follows:

In the vertical deflecting circuit:

Resistor	70=4 megohms
Resistor	79=400,000 ohms
Resistor	77=1 megohm
Resistor	81=.5,000 ohms
Condenser	73=.5 micro-farads
Condenser	83=.02 micro-farads
Resistor	85=.5 megohms
Resistor	107=.5 megohms
Resistor	111=.7 megohms
Condenser	109=.01 micro-farads

In the horizontal deflecting circuit:

Resistor	127=70,000 ohms
Resistor	129=4,000 ohms
Resistor	128=20,000 ohms
Resistor	153=200,000 ohms
Resistor	151=40,000 ohms
Resistor	149=9,000 ohms
Resistor	157=60,000 ohms
Resistor	155=100,000 ohms
Condenser	159=.0024 micro-farads
Resistor	167=2,000 ohms
Resistor	165=2,000 ohms
Resistor	163=2,000 ohms
Condenser	169=.03 micro-farads
Condenser	181=.0007 micro-farads
Transformer	183=5 to 1 step down ratio
Transformer	185=15 to 1 step up ratio

Other circuit values:

Resistor	201=1,000 ohms
Resistor	197=25,000 ohms
Resistor	199=.5,000 ohms
Condenser	207=.4 micro-farads
Condenser	205=.4 micro-farads
Condenser	203=.01 micro-farads

It may be noted that the variable resistors are usually set at a value equal to about one-half the resistance values given for them in the above table.

Circuit values are given by way of example in Fig. 13, these values being given in ohms and microfarads.

It will be understood that various other modifications may be made in my invention without departing from the spirit and scope thereof and I desire, therefore, that only such limitations shall be placed thereon as are necessitated by the prior art and are set forth in the appended claims.

5 I claim as my invention:

1. In combination, means for producing a saw-tooth voltage wave, a wave-utilization network including an amplifier tube and cathode ray deflecting means, said network having the characteristic that it causes the more gradually sloping portion of a saw-tooth wave to bend over, a correcting network, and means for coupling said first 10 means to said amplifier tube through said correcting network, said correcting network comprising resistive and reactive elements having impedance values so related that they act preferentially upon the low frequency components of said saw-tooth wave to compensate for said bending over.

15 2. The invention according to claim 1 characterized in that said correcting network consists of resistive and capacitive elements connected in series with each other and connected in shunt relation to the channel which includes said saw-tooth producing means and said amplifier.

20 3. The invention according to claim 1 characterized in that said correcting network consists of resistive and capacitive elements connected in series with each other and connected in shunt to the channel which includes said saw-tooth producing means and said amplifier, and further characterized in that said capacitive element is shunted by a variable resistor.

25 4. In combination, means for producing a saw-tooth voltage wave, a wave-utilization network including an electric discharge amplifier tube and cathode ray deflecting means, said network having the characteristic that it causes the more gradually sloping portion of a saw-tooth wave to bend over, and means for coupling said first 30 means to said amplifier tube, said coupling means including an amplifier tube and a correcting network on the output side thereof, said correcting network consisting of resistive and reactive elements connected in series and having such relative impedance values that they act preferentially upon the low frequency components of said saw-tooth wave to compensate for said bending over.

35 5. In a cathode ray tube deflecting circuit, means for producing a saw-tooth voltage wave, a transformer having a primary and a secondary, a pair of deflecting plates connected to said secondary, an amplifier tube having an input cir-

40 cuit and having an output circuit coupled to said primary, a correcting network, and means for coupling said first means to said input circuit through said network, said network including resistive and reactive elements connected in series with each other and in shunt to the channel which includes said first means and said amplifier tube.

45 6. The invention according to claim 5 characterized in that said reactive element is shunted by a resistor.

50 7. The invention according to claim 5 characterized in that said reactive element is a condenser.

55 8. In combination, a cathode-ray tube comprising an electron gun and a mosaic of insulated elements positioned in the path of the electron beam generated by said gun and also positioned at an acute angle to the axis of said gun, deflecting means for deflecting said electron beam vertically, deflecting means for deflecting said electron beam horizontally, means for producing a saw-tooth wave occurring at a relatively low frequency and for applying it to said first deflecting means, and means for producing a saw-tooth wave occurring at a relatively high frequency and for applying it to said second deflecting means, said last means comprising means for charging a condenser successively at a changing charging rate determined by said low frequency saw-tooth wave, an electric discharge tube, means for discharging said condenser successively through said tube at a changing discharging rate determined by said low frequency saw-tooth wave, and a network in said last saw-tooth wave producing means which comprises resistive and reactive elements, said network being located between said condenser and said second deflecting means, said network elements being so related that they filter out said low frequency saw-tooth wave and increase the amplitude of the low frequency components of said high frequency saw-tooth wave.

60 9. The invention according to claim 8 characterized in that said network comprises a filter section consisting of a condenser and resistor in series and a correcting section consisting of a condenser and resistor in series, said two sections being connected in series and so connected as to have the high frequency saw-tooth wave impressed thereacross, and further characterized in that said second deflecting means is coupled across said correcting section through an amplifier tube.

ALDA V. BEDFORD.
